United States Patent Office

Des. 199,122
Patented Sept. 15, 1964

199,122

HOLDER FOR TONGUE DEPRESSOR BLADE AND FLASHLIGHT

Roy C. Rowland, Jr., 1329 Kansas, Norman, Okla.

Filed Sept. 13, 1962, Ser. No. 71,682

Term of patent 14 years

(Cl. D17—3)

FIG. 1

FIG. 2

FIG. 1 is a top front perspective view of a holder for tongue depresser blade and flashlight, embodying my new design; and

FIG. 2 is a bottom rear perspective view thereof.

I claim:

The ornamental design for a holder for tongue depressor blade and flashlight, as shown.
